UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

THREAD-CONTROLLING MECHANISM FOR SEWING-MACHINES.

1,285,310.

Specification of Letters Patent. Patented Nov. 19, 1918.

Application filed August 8, 1917. Serial No. 185,065.

To all whom it may concern:

Be it known that I, JAMES R. MOFFATT, a citizen of the United States, residing at Chicago, in the county of Cook, State of Illinois, have invented certain new and useful Improvements in Thread-Controlling Mechanism for Sewing-Machines, of which the following is a description, reference being had to the accompanying drawing, and to the figures of reference marked thereon.

The invention relates to new and useful improvements in thread controlling mechanisms for sewing machines and more particularly to a thread controlling mechanism wherein a rotating member takes up and releases thread and a releasing finger and a check finger coöperate therewith in performing the thread controlling functions.

An object of the invention is to provide a detachable bracket for supporting both the releasing finger and the check finger so that said fingers may be assembled on the bracket and the bracket quickly attached to a sewing machine or removed therefrom.

A further object of the invention is to provide a supporting bracket for the releasing finger and the check finger, of the above character, and means whereby both the fingers may be vertically and simultaneously adjusted on said bracket, and independently adjusted horizontally.

A still further object of the invention is to provide means whereby the check finger may be angularly adjusted independently of the releasing finger.

These and other objects will in part be obvious and will in part be hereinafter more fully disclosed.

In the drawings, which show by way of illustration, one embodiment of the invention,

Figure 1 is a vertical sectional view through a part of a sewing machine having my improvement attached thereto;

Fig. 2 is a top plan view of the same;

Fig. 3 is a perspective view of the take-up cam, the operating shaft therefor, the supporting bracket and the releasing and check fingers carried thereby, the clamping screw 50 for the bracket also being shown as separated from the bracket;

Fig. 4 is a perspective view of the releasing finger and check finger and the devices for immediately supporting the same, the parts being separated to show the structure;

Fig. 5 is a side view of the take-up cam and the thread fingers, showing the thread just after it has been released from the shoulder of the cam by the releasing finger and as held by the check finger.

60

My improvement is directed to a thread controlling mechanism which is preferably used for the controlling of the looper thread of a chain stitch sewing machine. The thread controlling mechanism, broadly, to which the invention is applied is shown and described in the patent granted to R. G. Woodward, November 27th, 1906, No. 836,849. In said patent a rotary take-up cam operates to take up and release the looper 70 thread, and coöoperating with this rotary take-up cam is a releasing finger which causes the thread to be released from the shoulder of the take-up cam, and a thread finger which, for a certain period of time 75 retains the thread after it is released from the shoulder of the take-up cam.

The present invention is directed particularly to the means for supporting the thread fingers. Said invention consists broadly in 80 a detachable bracket on which both the releasing finger and the check finger are mounted and said bracket is capable of being quickly attached or detached from the sewing machine, carrying with it both the 85 thread fingers. The releasing finger is mounted for vertical adjustment in the bracket and may also be adjusted endwise in its supporting means. The check finger is mounted for angular adjustment on the 90 bracket and is also endwise adjustable in its supporting means.

Referring more in detail to the drawings, I have shown part of the sewing machine consisting of a bed plate 1 which carries 95 suitable bearings in which is mounted the main shaft 2. Mounted on this shaft is a take-up cam 3 consisting of two spaced disks 4-4. At each side of the take-up cam is an arm 5 having a guide 6 for the looper 100 thread. This arm is carried by a movable support 7. The take-up cam 3 is provided with a concentric thread retaining surface 8 and a non-concentric thread retaining surface 9. This non-concentric surface is disposed substantially radially of the cam and forms with the concentric surface a shoulder 10. There is also a second non-concentric thread retaining surface 11. Coöperating 105 with the take-up cam is a thread releas-

110

ing finger 12 and a check finger 13. These thread fingers extend between the disks. The cam rotates in the direction of the arrow, as shown in Fig. 1. The non-concentric surface will engage the thread passing through the thread guides 6 and will take up thread. The releasing finger slides the thread outwardly along this surface 9 and over the shoulder 10. The thread is released from the shoulder 10 just as the looper leaves the thread loop and the position of the check finger 13 determines the amount of slack in the looper thread when the needle is reaching lower end of stroke and previous stitch is being set and last needle loops pull up. The surface 11 controls the looper thread while the looper is at rear end of stroke to prevent too much slack which might otherwise cause the thread to whip under the looper point on next forward movement.

The parts above described broadly and the operation of the same is substantially the same as in the Woodward patent above referred to.

The thread fingers 12 and 13 are carried by a bracket 14. This bracket 14 is secured to an upwardly extending lug or bearing 15 formed integral with the bed of the machine and said bearing has a recess formed therein to receive the bracket and a screw 16 passing through an elongated slot in the bracket secures the same to the lug or bearing 15. The slot for the screw is elongated lengthwise of the bracket and permits a slight endwise adjustment of the bracket so as to bring the thread fingers between the disks of the take-up cam and thus insure a free movement of the cam without striking the fingers.

At the outer end of the bracket there is a socket 17 in which is mounted the post 18. Said post is adjustably held in the socket by a set screw 19. The upper end of the post is provided with a head 20 which has a transverse opening to receive the shank of the thread releasing finger 12. Said shank is adjustable endwise of the head and is held in adjusted position by a set screw 21. Adjustably secured to the head 20 is a supporting bracket 22 for the check finger 13. Said head has a transverse opening 23. The bracket 22 has a depending ear 24 formed with an opening 25. A screw 26 is adapted to pass through the opening 25 and into the transverse opening 23. Said screw is threaded into the opening in the head but the bracket is free to turn on the screw. By tightening the screw the bracket may be held in an adjusted position. Said bracket is provided with an opening 27 for the shank of the check finger 13 and the check finger is adjustable endwise in this opening. A set screw 28 serves as a means for clamping the check finger in the bracket 22.

From the above description, it will be ap-

parent that I have provided means for supporting the thread fingers which consists of a bracket adjustable so as to position the thread fingers properly between the disks of the take up cam. Both thread fingers are carried on a supporting post and are vertically adjustable so that the thread fingers may be adjusted to properly position the same for releasing the thread at the proper time. The releasing finger can also be adjusted endwise in the supporting head therefore and this together with the vertical adjustment of the releasing finger enables the releasing finger to be set so as to force the thread over the shoulder 10 just at the right time. The check finger may be angularly adjusted by shifting the bracket 22 and it also has an endwise adjustment. This angular adjustment is independent of the vertical adjustment of the check finger which takes place when the post is raised. This enables the proper setting of the check finger so that the non-concentric portion 11 of the take up cam will pass the same at the proper time and the thread be released.

In the drawings, I have shown my improved thread controlling mechanism as applied to the control of the looper thread of the sewing machine. The looper is indicated at 29. The looper thread is indicated at 1. This looper moves transversely of the line of feed. The feeding dog is indicated at 30 and the needles are indicated at 31. There are two needles shown.

It is obvious that minor changes in the details of construction may be made without departing from the spirit of the invention as set forth in the appended claims.

Having thus described my invention, what I claim as new and desire to secure by Letters Patent, is:—

1. The combination of a take up cam having a thread retaining surface, a releasing finger for releasing the thread from said retaining surface, a check finger for holding the thread after it is released, a detachable bracket for supporting said releasing finger and said check finger, means for supporting said releasing finger on said bracket, whereby it may be adjusted endwise thereon and means for supporting said check finger on said bracket, whereby it may be angularly adjusted and endwise adjusted thereon.

2. The combination of a take up cam having a thread retaining surface, a releasing finger for releasing the thread from said retaining surface, a check finger for holding the thread after it is released, a detachable bracket, means for supporting said releasing finger on said bracket, whereby it may be adjusted vertically and endwise thereon and means for supporting said check finger on said bracket, whereby it may be adjusted vertically and angularly and endwise thereon.

3. The combination of a take up cam hav-

ing a thread retaining surface, a releasing finger for releasing the thread from said retaining surface, a check finger for holding the thread after it is released, a bracket, a 5 vertically adjustable post carried by said bracket, means for supporting said releasing finger on said post whereby it may be adjusted endwise thereon and means for supporting said check finger on said post where- 10 by it may be angularly adjusted and endwise adjusted thereon.

4. The combination of a take up cam having a thread retaining surface, a releasing finger for releasing the thread from said re- 15 taining surface, a check finger for holding the thread after it is released, a bracket, a vertically adjustable post carried by said

bracket, said post having a head at its upper end provided with an opening for the thread releasing finger, said thread releasing finger 20 being adjustable endwise in said opening, a second bracket pivoted to said head and having an opening therein adapted to receive the shank of the check finger whereby said check finger may be adjusted endwise therein 25 and means whereby said second bracket may be angularly adjusted on said post and held in adjusted positions.

In testimony whereof, I affix my signature, in the presence of two witnesses.

JAMES R. MOFFATT.
